(57) **CLAIM**

The ornamental design for a water treatment system housing, as shown and described.

DESCRIPTION

FIG. 1 is a top perspective view of the present water treatment system housing;

FIG. 2 is a front view of the water treatment system housing of FIG. 1;

FIG. 3 is a rear view of the water treatment system housing of FIG. 1;

FIG. 4 is right side view of the water treatment system housing of FIG. 1 both sides being mirror images of each other;

FIG. 5 is a top view of the water treatment system housing of FIG. 1; and,

FIG. 6 is a bottom view of the water treatment system housing of FIG. 1.

The subject matter depicted in broken lines depicts portions of the present water treatment system housing that are not part of the claimed invention.
